UNITED STATES PATENT OFFICE

LAMBERT SCHMIDT, OF BROOKLYN, NEW YORK

THEFTPROOF LAMP

Application filed October 3, 1936. Serial No. 140,414.

This invention relates to theft proof lamps and has for its object to provide a lamp of incandescent bulb type which has means thereon rendering the lamp theft proof, 5 that is, renders the lamp such as to be impossible to be taken from the socket. The means utilized by this invention are such that it is at the will of the owner of the lamp to determine whether he desires to 10 utilize the lamp in theft proof fashion or whether he desires to use the lamp in the ordinary manner permitting its ready removal.

The invention has for its object to provide a very simple device applicable to the standard screw threaded base of an incandescent lamp bulb, coating with a standard socket as is generally in use.

For this purpose the invention comprises a 20 spherical or cylindrical member separate from the lamp base which at the will of the user may be readily applied to the lamp base and when so applied and the lamp base inserted into the socket the lamp becomes secured thereto and cannot be removed unless the lamp be broken.

An embodiment of my invention will be hereinafter described and shown in the drawings and the invention will be finally pointed out in the claims.

In the accompanying drawings Fig. 1 is a front view of a standard lamp base with a lamp bulb partially shown and with my invention means applied to said standard base. 35 Figure 2 is a vertical central section taken on line 2—2 of Fig. 1, seen in the direction of the arrows.

Figure 3 is a substantially horizontal view taken on line 3—3 of Fig. 2.

Figure 4 is a perspective view of a collar adapted to hold the locking member.

Figure 5 is a perspective view of a detail member.

Figure 6 is a diagrammatic view of a horizontal section showing a cooperation of the parts.

Figure 7 is a transverse diagrammatic view showing a cooperation of the parts and

50 Figure 8 is a perspective view of a cylind-

rical roller adapted to replace the spherical member shown in Figures 1 to 7.

Similar characters of reference indicate corresponding parts throughout the various views.

Referring to the drawings and more particularly to figures 1 and 2, the well-known lamp bulb 10 is suitably secured to the standard base 11 by means of cement 12 or the like and this standard base 11 has the usual contact point 13. The base 11 is provided with the standard threads 14 as shown. These parts are all well known. Within the threaded portion of the base 11 I arrange a split collar 15 as shown in Figure 4 which is provided with a circular opening 17 and is provided at its periphery with notches or cutouts 18 which are adapted to be engaged by pinched in portions 19 of the threaded base. These pinched in portions 19 engaging the recesses or cut-outs 18 serve for the purpose of holding this collar 15 in position against rotation. The periphery of the collar 15 is further provided with a larger cut-out or notch 20 and the periphery of the collar is cut down as indicated to form a cam face 21. Along the longitudinal surface of the threaded portion 14 of the base member 11 there is arranged a spring-like resilient member 25 having a bent over portion 26 and a handle portion 27. This member 25 is provided with bends or corrugations so arranged as to register closely with the threaded portion of the base member 11 as clearly seen in Figure 2, and the bent over portion 26 extends into the notch 20 of the collar 15 with the free end portion 26 abutting against the innermost surface of the notch 20. The base, that is the screw threaded portion thereof, is provided with a 55 tapered slot 29 arranged longitudinally of one of the threads of the threaded portion. The larger portion 30 of this slot 29 registers substantially with the notch 20 in the collar 15 and the tapering portion of the slot or opening 29 registers substantially with the cam face 21 of the collar 15. A spherical member or ball 31 of a suitable non-compressible material, although a lead ball of

60 suitable rigidity may also answer the pur- 65 pose, is provided and is held in the slot 29. The handle portion 27 of the member 25 is 70 provided with a slot 32 which registers with the slot 29 and the handle portion 27 is 75 provided with a slot 33 which registers with the slot 32. The member 25 is provided with a 80 bent over portion 34 which registers with the slot 33. The member 25 is provided with a 85 bent over portion 35 which registers with the slot 34. The member 25 is provided with a 90 bent over portion 36 which registers with the slot 35. The member 25 is provided with a 95 bent over portion 37 which registers with the slot 36. The member 25 is provided with a 100 bent over portion 38 which registers with the slot 37.

pose, is entered through the enlarged portion 30 of the slot 29 formed in the screw threaded member of the base 11 and into the notch 20, the resilient member 26 being slightly compressed thereby. The ball 31 is positioned in the notch 20 with the aid of a thin coating of wax or the like which acts to temporarily hold this ball 31 in the desired position as shown in Fig. 1. Instead of a spherical member or ball 31 a cylindrical member indicated by 32 in Fig. 8 may be provided. With the parts in the position as shown in Figs 2 and 3, the base 11 is then inserted into the socket, not shown in detail 10 as the same is well-known. The bulb with the base 11 is then rotated for the purpose of inserting the lamp. After it has been inserted to some extent, the protruding portion of the ball 31, that is that portion which 15 protrudes through the slot 29 enters the corresponding registering valley of the socket. Upon continued rotation, the base enters fully into the socket, without impedance as the protruding surface of the ball 31 registers with that portion of the threaded member which has been cut away, and glides along the corresponding valley of the socket 20 thread. 25

When, however, the bulb is rotated in an opposite direction as is the case when it is 30 desired to remove the bulb, then the ball 31 will be forced out of its position in the notch 20 and along the cam face 21 of the collar 15 thereby becoming jammed between the 35 cam face 21 and the socket wall 35. Simultaneously with such jamming the base and the socket will be moved eccentrically with each other as shown diagrammatically in Fig. 6, and also axial displacement of the 40 base with relation to the socket will take place, thus bringing their respective threads into close frictional contact and effectively locking the parts against turning movement. This jamming of the ball 31 between the 45 wedging surface 21 and the interior of the socket 35 is clearly shown in Fig. 6. A similar operation of parts is shown in Fig. 7 where the wall of one of the threads indicated by 36 is slightly moved to the extent 50 permissible by the inherent resiliency of the material of which such a socket is made. The arrow 37 indicates the direction of the unscrewing of the base 11 and the position 55 of the convolution indicating the base thread is there shown axially in angular position with the corresponding thread 35 of the socket. It is the angular relationship of these parts combined with the wedging action of the surface 21 and the eccentric relationship of the socket and base that brings 60 about a very efficient jamming action.

One advantage of my improved theft 65 proof device is that bases like those shown in the drawings may be readily manufactured, and supplied to the users since the

standard base now in common use is simply provided with a washer such as shown in Fig. 4, the member such as shown in Fig. 5 and the locking member 32 or the ball 31. The user may then determine whether he 70 desires to use this base for this lamp as a theft proof lamp or whether he wishes to use it as a non-theft-proof lamp. In the latter case he does not have to utilize the locking member 31 or the other locking member 32 and he simply uses the lamp base in the ordinary manner. If, however, he desires to have a theft proof lamp he then places one of the balls or other locking obstruction in position preferably with the aid 75 of a little wax as a temporary holding means and thereby converts the lamp and base into a theft proof lamp. If the lamp has been used as a theft proof lamp it can only be removed by destroying the glass bulb 10 after which the member 27 is pulled out of the base 11 and by pulling the member 27 80 out of its position, that is, removing the portion 26, the ball 31 can fall into the notch 20 and thereby be removed from the same, 85 which with the removal of the locking means permits the unlocking or the removal of the base.

I have described and shown an embodiment of my invention but it is clear that 90 changes may be made therein without departing from the spirit of my invention, as defined in the appended claims.

I claim as new and desire to secure by Letters Patent:

1. A lamp for a standard threaded socket comprising a standard threaded base, an opening in the threaded portion of the base having an opening, means for holding a locking member, and a locking member adapted to be inserted into the opening and held by said means when said lamp is to be rendered theft proof, and designed to be entirely omitted therefrom when said lamp is to be non-theft proof.

2. A theft proof lamp for a standard threaded socket comprising a standard threaded base, the threaded portion of the base having an opening, a split collar within the standard base, having a notch and a cam face, and a locking member separate from said base, and adapted to be inserted through the opening into said notch of the split collar for locking the base to the socket, when said locking member is acted upon by the 115 cam face of the collar.

3. A theft proof lamp, comprising a standard threaded socket and a standard threaded base, the threaded portion of the base having a slot of tapering shape, a collar within the base and seated within and along the interior portion of the threads of the base, and having a notch and a cam face, a spring member seated within the notch of the collar and extending to the exterior of 125 130

the base and bulb, and a locking member within the tapering slot of the base and seated against the spring member in the notch.

5 4. A theft proof lamp according to claim 2, in which the locking member protrudes from the base to the extent of the thread cut away at the slot in the base.

10 5. A theft proof lamp, according to claim 2 in which locking action is aided by the eccentric and angular relationship of the base and socket.

15 6. A theft proof lamp, according to claim 3, in which the extending spring member has corrugated portions in registration with the threads of the base, and the collar has peripheral portions to be engaged by the base to prevent the collar from rotating.

20 7. A theft proof lamp, according to claim 3, in which the spring member is adapted to be moved out of holding position to release the locking member, to permit the removal of the locking member and the removal of the base from the socket.

25 8. A theft proof lamp for a threaded socket comprising a threaded base, said base having an opening in its threaded portion, a locking member adapted to be disposed in the opening and to protrude beyond the exterior surface of the base to engage the socket, and means within the base for wedging the locking member against the wall of the socket when the base is rotated in one direction.

30 9. A theft proof lamp for a threaded socket comprising a threaded base, said base having an opening in its threaded portion, and a locking member separate from said lamp base, the opening being large enough to permit the insertion of the locking member into the base, and means carried by the base to cooperate with the locking member when same has been inserted into the base to prevent removal of the lamp from the socket.

35 40 45 50 55 10. A lamp having a threaded base for engagement in a standard threaded socket, and means for locking the lamp in connection with said socket against removal therefrom including a locking member, said lamp base having means to support said member for sliding contact with the socket wall upon threading the lamp base into the socket, and cam means carried by the lamp base and co-acting with said locking member upon turning the lamp base in the opposite direction to project said member radially of the lamp base and into locking engagement with the socket wall.

60 In testimony that I claim the foregoing as my invention, I have signed my name hereto.

LAMBERT SCHMIDT.
